(57) **CLAIM**

The ornamental design for a vegetable shredder, as shown and described.

DESCRIPTION

FIG. 1 is a top perspective view of a vegetable shredder; FIG. 2 is a bottom perspective view thereof, shown separately from the push block, blade, and container to show aspects of the design that are not visible when combined; FIG. 3 is an exploded bottom perspective view thereof showing the included push block, blade, and container; FIG. 4 is a left side view of thereof; FIG. 5 is a right side view thereof; FIG. 6 is a bottom plan view thereof; FIG. 7 is a top plan view thereof; FIG. 8 is a front view thereof; and, FIG. 9 is a rear view thereof.
All broken lines illustrate portions of the vegetable shredder that form no part of the claimed design.
